UNITED STATES PATENT OFFICE.

JOHN A. BRADSHAW, OF LOWELL, MASSACHUSETTS, ASSIGNOR TO DANIEL WALKER, TRUSTEE, OF SAME PLACE.

CARDING-ENGINE.

SPECIFICATION forming part of Letters Patent No. 329,356, dated October 27, 1885.

Application filed December 18, 1884. Serial No. 150,682. (No model.)

To all whom it may concern:

Be it known that I, JOHN A. BRADSHAW, a citizen of the United States, residing at Lowell, in the county of Middlesex and Commonwealth of Massachusetts, have invented 5 certain new and useful Improvements in Carding-Engines, of which the following is a specification.

My invention relates to carding-engines; 10 and it consists in the devices and combinations hereinafter described and claimed, the object of such devices and combinations being to strip and doff the main cylinder.

In the accompanying drawings, on four 15 sheets, Figure 1 is a right-side elevation of a carding-engine provided with my improvements, the cam secured to the main shaft, a part of the upper pawl-lever and its ratchet, and a part of the stripper-cam, stripper-lever, and 20 its arch being shown by dotted lines, the carding-cylinder also being shown by dotted lines, and parts of the arch of the frame being broken away to show the carding-cylinder; Fig. 2, a left-side elevation of the same; Fig. 25 3, a side elevation of the stripper-cylinder, comb-shaft, and gearing; Fig. 4, a section of the stripper-cylinder on line $x-x$ in Fig. 8, the comb-shaft and comb-carrier being in elevation; Fig. 5, a top view of a carding-engine 30 provided with my improvements, the arrow on the top indicating the direction in which the carding-cylinder rotates; Fig. 6, a diagram, the large circle in full line indicating the carding-cylinder, the dotted circle around 35 it indicating the ends of the teeth of said cylinder, the small upper and lower circles indicating, respectively, the doffing-stripper and the lower stripper or stripper proper, to show the different depths to which the teeth of said 40 stripper enter the clothing of the carding-cylinder; Fig. 7, an elevation of the inner side of the lower ratchet, to show the shipping-cam and the lifting-cam secured thereto; Fig. 8, a 45 plan of the stripper-levers, the lower ratchet, shipping-rod, clutch-lever, clutch-pulley for operating the lower stripper, said stripper, a part of the carding-cylinder, and frame being in section, and said stripper and carding-cylinder being turned ninety degrees downward

and backward, to show how the teeth of said 50 stripper enter the clothing of the main cylinder.

The frame A, arch A', feed-rolls F F', the lower roll, F, provided with a gear, f, which takes into a pinion, f', secured to and revolving 55 with the roll-driving pulley f², which roll-driving pulley f² is driven by a band, f³, from a small pulley on the main cylinder-shaft C', the feed-rolls F F' being geared together, the gear f⁴ on the lower roll, F, being connected 60 through the intermediate gear, f⁵, to the gear f⁶ on the end of the fluted lap-feeding roll, the fast, P, and loose, P', pulleys on the cylinder-shaft C', the main cylinder C, and the top-flats T are all of the usual construction and 65 operation, except as hereinafter specified. The cylinder-shaft C' is provided with a cam or wiper, c, between the frame A and the fast pulley P, which cam, when said shaft revolves, strikes once in every revolution 70 upon the top of a pawl-lever, L, pivoted below and in front of said main shaft to the side of said frame, the rear end of said pawl-lever having a pawl, l, pivoted thereto and depending therefrom, which pawl l takes into 75 a ratchet-wheel, R. The ratchet R turns on a stud, r, projecting from the side of said frame, and has cast or otherwise secured thereon a cam, c', similar to the cam c above named, which cam c', in each revolution of 80 said ratchet R, strikes once upon the top of another pawl-lever, L', pivoted on the side of said frame in front of and below said stud r. The pawl-lever L' has pivoted to it and depending from it a pawl, l', which takes into 85 another ratchet, R', which is secured to a shaft, S, which extends through the machine from side to side and turns in the said frame. Each end of the shaft S is provided with a cam, c² c². Outside of said frame, near the 90 front of the machine, is pivoted at p' a lever, L² L², which extends to the back of the machine, and is provided near its free end with an arch, l² l², from the crown of which depends a projection, l² l², which once in every revolution of the shaft S is struck by the cam c² c² and lifted. Supported in bearings in said levers L² L², and extending across the machine 95

below the main cylinder C, is the stripper proper, W. This stripper W consists of an outer cylindrical shell, w, provided with four longitudinal slits, w', extending nearly from 5 end to end of the same. Between the slits the cylinder is strengthened by longitudinal ribs w², and also at the slits the shell w is thickened, or provided with ribs w³, the adjacent faces of which are beveled toward the slits. To 10 the ends of the shell w are secured hollow journals w⁴, concentric with said shell, said journals being provided with circular heads w⁵, which enter the ends of said shell and are secured therein by pins or screws w⁶, driven 15 through the shell into said heads. The journals of the shell extend only part way through the journal-boxes L⁵, secured on the levers L² L². The comb-shaft v is square, except at its journals, and is provided (see Figs. 4 and 8) 20 with four projecting arms, v', near each end of the square part of said shaft, and these arms are provided with circular openings v². In these circular openings are held the rods v⁹, which reach from end to end of the square 25 part of the shaft, parallel therewith. The rods v⁹ are provided with straight rows of teeth or needles v⁸, which project outward into or through the slits w', as explained below, the rods v⁹ and teeth v⁸ forming combs V. The slots 30 v⁴, extending out from the openings v², are intended to allow the combs V to be inserted in and removed from the arms endwise without removing the arms from the shaft or the teeth from the comb. The shaft v is not concentric 35 with the shell, but turns in separate bearings in the same pillow-blocks, B B, and may be covered by a separate cap, b b', indicating the cap of the shell. The shell w is provided at one or both ends with an internally-toothed 40 gear, w⁶, concentric with the axis of said shell, as shown in Figs. 3 and 8, and the shaft v is provided with a smaller externally-toothed gear, v¹⁰, concentric with the axis of said shaft, which gear v¹⁰ engages with the gear w⁶, and 45 which has the same number of teeth as said gear w⁶. The faces of each tooth of each gear w⁶ v¹⁰ are preferably planes which meet each other at an angle of about twenty degrees, the teeth on the inner gear, v¹⁰, and the teeth of the 50 outer gear, w⁶, being separated by spaces, as shown. It is evident that rotating the shaft v will rotate the shell, and that if said shaft have a uniform rotary motion the surface-speed of the shell will also be uniform. It is 55 apparent that the teeth v⁸ of each comb V, if of proper length, (the axis of the shaft being above that of the shell w, as shown,) will project above the shell when such comb is above the shaft v, and will be gradually drawn into 60 the shell as the shaft is rotated, so that when such comb is directly below the shaft the teeth will be wholly within the surface of the shell. The shaft v has secured to it a disk, v⁵, which has a stud, v⁶, projecting therefrom parallel 65 with said shaft v, and there is a pulley, v⁷, which slides freely and turns loosely on said shaft,

and is provided with a similar stud, v⁸, at an equal distance from said shaft v, the disk v⁵ and the pulley v⁷ forming the parts of a clutch-pulley of common construction. The hub of 70 the pulley v⁷ has an annular groove, with which the forked end n of the lever N engages. The lever N is pivoted at n' to a bracket, l, projecting from the lever L², which is on the side of the machine opposite the ratchet R', and 75 its rear end is pivoted to a shipping-rod, N', which reaches across the machine and slides in bearing l' in the lever L² L². The ratchet R', above named, is provided on its inner face with a cam, r', or arc-shaped projection with 80 beveled ends, which cam r', as said ratchet R' is rotated, pushes the rod N' endwise and operates the lever to move the pulley v⁷ into an engagement with the disk v⁵. The rod N' is restored to position by a spring, N², surrounding 85 said rod, and compressed between the frame A and a pin, n², driven through said rod. The pulley v⁷ rotates at all times when the carding-cylinder is in motion, there being secured to the main shaft C a large gear, M, which takes 90 into a pinion or small gear, M', the latter being concentrically secured to a band-pulley, M², and turning with it on the stud m, which projects from the side of the frame A, and the pulley M² being connected by the band m' to 95 the clutch-pulley v⁷. It will appear from Figs. 1 and 7 that the clutch is closed by the above-described action of the cam r for some time before the levers L² L² are raised by the action of the cams c² c². The object of this is to let the 100 stripper W attain its full speed before being applied to the surface of the cylinder C. If the stripper W were running slower than the main cylinder at the time of lifting the stripper into contact with the cylinder, the teeth of the 105 cylinder would be broken, and it is necessary that the stripper should revolve much more rapidly than the main cylinder—that is, with a greater surface-speed—in order to clean the clothing of the cylinder, because the teeth of 110 the cylinder are hooked in the direction in which they move. The stripper so constructed and operated is at intervals, the frequency of which will depend on the number of teeth in ratchet R R', raised by the means 115 above described high enough for the comb at the top of the cylinder to reach in between the teeth of the main cylinder and catch the cotton and draw it forward off from the teeth of said cylinder. As the stripper continues 120 to revolve the teeth of the comb will be retracted into the shell of the stripper through the slots, which are too fine to admit the cotton or other fibers being carded, and the teeth of the comb will be stripped by the surface of the shell and deposited on the floor below the cylinder. The above-described stripper is automatic in its action, and by changing the ratchets R R' may be made to 125 strip at any desired intervals, and it does not require the carding-engine to be stopped, which is necessary where the cylinder is 130

stripped by hand. I use a doffing-stripper, W' , in all respects like the stripper W , except that it is driven continuously while the carding-cylinder is in motion, its square shaft 5 w^7 having secured thereto a band-pulley, K , connected by the band K' to another band-pulley, K^2 , which turns on a stud, K^3 , projecting from the side of the frame A , the last-named pulley, K^3 , having secured to it a pinion, K^4 , concentric therewith, which takes 10 into the large gear M above described. The axes of the central shaft and shell, w^8 , of the doffer-stripper, like those of the corresponding parts in the lower stripper, are in the same 15 plane with the axis of the carding-cylinder C , the axis of the central shaft being nearer to the carding-cylinder than the axis of the shell, so that the greatest projection of any combs w^9 of the doffer-stripper is when such combs 20 nearest the cylinder and its teeth or needles w^{10} are in the same plane with the axis of the cylinder C . The teeth of the doffer-stripper do not enter the teeth of the card-clothing on the cylinder to as great a depth as the teeth 25 of the stripper, as the doffer-stripper is not intended to thoroughly strip the said cylinder, but only to take the place of the ordinary card-clothed doffer in forming a sliver. The combs of the doffer-strippers are cleaned just as 30 the combs of the stripper proper are cleaned—that is, by the combs being drawn into the shell as the doffer-stripper rotates. The doffer-stripper is applied to the cylinder a little above the frame A proper, near the front of the main 35 cylinder, portions of two or more top-flats being removed for that purpose. The fibers doffed from the cylinder are thrown forward onto the bonnet or top-flats T , just in front of the doffer, and are taken thence by the rolls 40 U U' , which rotate in the direction shown by the arrows and draw the doffings forward between them, and thus form a fleece, which, by the rotation of said rolls U U' , is delivered in front of the rolls into a trumpet, w^{11} , substantially 45 of the usual construction and operation, from which trumpet the fleece is drawn in the usual manner to form a sliver. The lower fleece-roll, U , is provided with a gear, u , which takes into a pinion, u' , turning on a stud projecting from the side of the frame A . A band-pulley, u^2 , is secured to and turns the pinion u' , and is connected by a belt or band, w^6 , to a small pulley on the main shaft. The upper roll, U' , is driven by frictional contact with 50 the fleece between it and the lower roll, U , and turns loosely between the studs w^4 or roll-stand secured to the top-flats.

I claim as my invention—

1. The combination, with the frame, carding-cylinder, and main shaft of a carding-engine, and means of rotating said cylinder-shaft, of a cam secured to said shaft, a pawl-lever pivoted to said frame, adapted to be struck by said cam, and provided with a pawl, a ratchet pivoted to said frame and adapted to be engaged by said pawl and to be rotated thereby, the hub of said ratchet being provided with a cam which rotates therewith, another pawl-lever secured to said frame and adapted to be struck by said last-named cam and provided with a pawl, another ratchet pivoted to said frame and adapted to be engaged by said last-named pawl and to be rotated thereby, a shaft to which said last-named ratchet is secured, said shaft extending through said frame from side to side thereof, and being provided with cams, stripper-levers pivoted on opposite sides of said frame and provided near their free ends with arches having downward projections adapted to be struck by the cams last named, and a stripper-cylinder arranged beneath and parallel with said carding-cylinder and having its journal-bearings on the levers last named, whereby said stripper-cylinder is automatically brought at intervals into contact 85 with said carding-cylinder, as and for the purpose specified.

2. In combination with the stripper-levers and stripper-cylinder, and means, substantially as described, of raising said levers, one of the 90 said levers being provided with a bracket, the clutch disk secured to the shaft of said stripper-cylinder and provided with a stud parallel to said shaft, the clutch-pulley provided with a stud at an equal distance from said 95 shaft with the stud in said disk, said clutch-pulley turning loosely and sliding freely on said shaft and having a hub provided with an annular groove, a lever pivoted to said bracket and having at one end a fork to engage with the groove in said hub, a rod pivoted to the end of said last-named lever and sliding in said shipping-levers, a ratchet provided with a cam adapted to strike the free end of said rod and to move said rod longitudinally, and means, substantially as described, of rotating said ratchet, as and for the purpose specified.

JOHN A. BRADSHAW.
